PULPSTONE

George N. Jeppson, Worcester, Mass., assignor to
Norton Company, Worcester, Mass., a corpora-
tion of Massachusetts

Application October 30, 1945, Serial No. 625,523

7 Claims. (Cl. 51—206)

1

The invention relates to pulpstones.

One object of the invention is to provide a strong pulpstone. Another object of the invention is to provide a pulpstone which can be easily repaired.

Another object of the invention is to provide such a construction in which the portions of the block which are held by the bolts are under compression. Another object of the invention is to provide a sizeable surface of the block engaged by a clamping bolt or a washer thereon.

Another object of the invention is to provide a construction having one or more of the characteristics indicated with clearance for relative movement between the blocks and the bolts in a circumferential direction of the stone. Other objects will be in part obvious or in part pointed out hereinafter.

The invention accordingly consists in the features of construction, combinations of elements, arrangements of parts, and in the several steps and relation and order of each of said steps to one or more of the others thereof, all as will be illustratively described herein, and the scope of the application of which will be indicated in the following claims.

In the accompanying drawings in which is shown one of many possible embodiments of the mechanical features of this invention.

Figure 1 is a sectional view in a plane perpendicular to the axis of a pulpstone constructed in accordance with the invention;

Figure 2 is a perspective view of an abrasive insert which is used when a broken block is replaced with a new block;

Figure 3 is a view of a single pulpstone block from the inner side thereof;

Figure 4 is a view of a fragment of the stone in the same section as shown in Figure 1 but on an enlarged scale;

Figure 5 is a sectional view in an axial plane taken along the line 5—5 of Figure 4;

Figure 6 is a fragmentary sectional view, on a further enlarged scale taken along the line 6—6 of Figure 4.

Referring first to Figure 1 the pulpstone comprises a plurality of bonded abrasive blocks 10 and a central concrete core 11. The blocks 10 are arranged in circular rows to form a hollow body of abrasive blocks with an outer surface of revolution. While in most cases this outer surface of revolution will be a cylinder it is contemplated that other surfaces may be formed, such as cones, ellipsoids and paraboloids. While the invention principally relates to pulpstones,

it may be embodied in stones for pulp refining engines or for any other purpose.

The blocks 10 may be made of any suitable abrasive such as silicon carbide or aluminum oxide, bonded by any suitable bond, vitrified bond being preferred. Other bonds such as phenol-formaldehyde resin, rubber, shellac, magnesium oxy-chloride or metal bond may be used. The manufacture of the bonded abrasive is known and hence need not further be described herein.

Between blocks 10 of the pulpstone is incorporated filler material 12 preferably at all faces of the blocks which would otherwise be in contact with a face or faces of another block. Since such filler material 12 may have no abrasive properties, it is desirable to so arrange the blocks that there will be no true circle on the surface of the stone entirely along the filler material 12. This may be done in several different ways, such as by shaping the stones to make zigzag joints such as shown in patent to Larsson No. 2,078,451. The filler material 12 may be of any desired type but preferably is a material which adheres to the faces of the blocks 10 and has some strength but which will deform in response to excessive circumferential and axial forces, such as, caused by overheating of the stone. I prefer the filler material such as described in patent to Larsson No. 2,054,771 and I have found that the use of synthetic rubber actually improves the quality of this material. As described in the Larsson patent the filler material is rubber containing enough sulphur to vulcanize to a hard rubber together with granules of cork interspersed therein to form collapsible pockets.

Referring now to Figure 3 in connection with Figure 4, each block 10 may have an outer surface 13 in the shape of a segment of a cylinder or cone etc., an inner surface 14 which is flat except for a plurality of grooves 15, a pair of side surfaces 16 which are substantially in axial planes of the stone, and end surfaces 17 which, as shown, make small dihedral angles with radial planes of the stone perpendicular to the axis.

As shown in Figures 4, 5 and 6, each stone 10 has on each side 16 a pair of pockets 20—20 with grooves 21—21 extending from the face 14 to pockets 20. The bottoms of the pockets 20 form seats 22. Referring to Figures 3 and 4, I provide metal bars 23, preferably of steel, the ends of which are preferably milled off or countersunk to provide surfaces substantially tangent to circles concentric with the stone at said ends. In these milled-off ends are holes 24. I further provide washers 25 in the pockets 20 seated on the seats

22. Bolts 26 having bolt heads 27, extend through the washers 25, through the holes 24, through sleeves 28, through washers 29 and into nuts 30, the inner ends of the bolts 26 being threaded as shown at 31.

A block 10 is first assembled with a pair of bars 23, four bolts 26, four washers 25, four washers 29, four nuts 30 and four sleeves 28. After assembling these parts to a block as shown, the nuts 30 are tightened to put a pre-tension on the bolts 26 sufficient to hold the blocks 10 to the core 11 against all forces tending to remove the blocks 10 from the center 11. Enough pre-tension can be given the bolts 26 so that blocks 10 even when subjected to destructive forces will not move from the support 11 until the abrasive itself gives away.

After the required number of blocks 10 have thus been provided with bars 23, bolts 26, washers 25, washers 29 and nuts 30, they are built up into an annulus with sheets of material 12 between them. The annulus is then securely clamped together by circumferential clamps and the entire structure is then placed in an oven and heated to around 160° centigrade for a period of about 24 hours to vulcanize the material 12. A plurality of concentric steel cages comprising steel hoops 35 spaced apart by steel or iron spacing members, not shown, are then placed inside the annulus of blocks 10 in the position indicated in the drawings. As illustrated in Figure 5 the hoops 35 of the two outer cages can be placed between bolts 26. This entire assembly is mounted upon the bottom plate of a mold and a pair of iron or steel mold sleeves are then placed in the center thereof. The molding equipment is not shown as it is now well known in the art and forms no part of the final article. Concrete consisting of Portland cement with sand and a suitable amount of trap rock is then poured into place between the mold sleeves and the annulus of the blocks 10 and allowed to set.

The pulpstone constructed as above described is well able to resist mechanical stresses and heat shock. Each block 10 is securely clamped to a pair of bars 23 which are preferably made of steel. Large portions of each block 10 (under the shoulders 22) are under compression. Yet no tightening of anything is necessary after the annulus is built up. The blocks 10 are keyed to the concrete center 11 because concrete flows into the grooves 15 and forms keys. These keys drive the blocks. In cases of circumferential expansion of the blocks, the deformable material 12 provides the safety valve, and this same material serves to prevent the breakdown of the rear (in relation to direction of rotation) edges of the blocks.

It is almost certain that the bolts 26 will practically never come out of the concrete center 11. The blocks 10 cannot come out unless large portions of them break off. This will rarely happen, but if and when it does the broken block or blocks can be readily replaced. As shown in Figure 1, I may provide blocks 10a with portions cut out which are of the shape of abrasive plugs 40 one of which is shown in perspective in Figure 2. The bolt heads 27 have screw driver slots and the bolts 26 can be screwed out of the nuts 30. After the bolts 26 which held the broken block have been thus removed, the washers 25 are inserted in the pockets 20 of a block 10a, the bolts 26 are passed therethrough, the block 10a is placed in position and the bolts 26 tightened. Then four plugs 40 are cemented in place and the pulpstone is repaired.

From an examination of Figure 4, it will be noted that the bolts 26 can be flexed a few thousandths of an inch before contacting the sleeves 28. This clearance prevents fracture of the bolts 26 or of the blocks due to expansion of the blocks or differential expansion between the blocks and the stone.

The bolts 26 may be made of any suitable steel which is capable of being put under tension without permanently deforming. It is desirable that the bolts 26 as well as the washers 25 be plated or made of stainless steel in order that pulp water, which does sometimes penetrate the porous abrasive material of the blocks 10, shall not cause the pulpstone to deteriorate by rusting of the bolts or washers. It is also desirable that the seats 22 be true'd to make a smooth surface for engagement by the washers 25 or that washers of copper or other soft metal be provided between the washers 25 and the seats 22. Alternatively, the washers 25 can be made of steel which is soft enough to conform to the irregularities of the seats 22.

Another preferred feature of the pulpstone is that the bases of the blocks 10 are preferably stronger than the grinding portions of the blocks 10. By "base" I mean that area of a block which is included between the face 14 and the level of the seats 22. The bases of the blocks do not at any time grind pulp and accordingly no consideration need be given to the abrasive properties of the bases. In fact, the portions of the blocks which do the grinding constitute the volume which is radially outward of the tops of the bolt heads 27. The volume of the blocks in the space between the tops of the bolt heads 27 and the seat 22 constitutes a sort of intermediate zone which might be the same as the outer abrasive portion of the block or the same composition as the base.

It is known in the art how to make the bases of the blocks stronger than the outer or abrasive portions of the blocks. There are several different ways to do this but one means which is satisfactory consists in loading the lower portion of the mold which forms the block with abrasive of smaller grit size and possibly also providing a greater volume percentage of abrasive. It is the lower part of the mold which forms the base.

Alternatively, the outer or abrasive portions of the blocks 10, that is to say, between the surfaces 13 and the level of the tops of the bolt heads 27, may have an open porous structure. For example, if fused alumina abrasive of 24 grit size is mixed with clays, selecting quantities to provide 44 volume per cent of abrasive and about 14.3 volume per cent of bond, and to this is added enough coke in granule form to make 15 volume per cent in the pressed article, the coke being of grit size 12-14, there results a suitable mixture for the abrasive portion of the block which will have large pores, namely, from grit size 12 to grit size 14. If a second mixture is made of the same abrasive of the same grit size and the same bond, but calculated to give 50 volume per cent of abrasive and 11.5 volume per cent of bond, we have a suitable mixture for the base of the block which will result in a base much stronger than the abrasive portion of the block. These two mixtures can be simultaneously pressed to form an integral block. Instead of using coke to form the large pores, any other material which will be eliminated during the burning of the block may be used. Another example is naphthalene.

It has been found that for certain types of pulp grinding, a porous abrasive containing large

pores, generally referred to as induced pores, gives better performance. It is desirable in this and other cases to form a base portion of the block which is stronger than the outer or abrasive portion.

It will be seen from the drawings that the seats 22 have a relatively wide area which is contacted by the washers 25. Thus a large portion of a block must break before it can come out of the pulpstone. Nor can the blocks become loose due to contraction of the pulpstone because they are held to the concrete center under tension and the force is exerted between the seats 22 and the washers 29 via nuts 30. Yet despite this feature the only tightening operation is done before the blocks are set in position to form the stone. I prefer to use washers 25 to fit the seats 22, but alternatively large bolt heads might directly contact the seats. Also while I prefer to place the bolt heads 27 in the pockets 20 and the nuts 30 in the concrete, this arrangement might be reversed or two nuts might be used.

A special problem was involved in the formation of the pockets 20 and the grooves 21. Abrasive mixes in a mold behave somewhat as does a fluid but they do not fully follow Pascal's laws. Such material under pressure will form a reentrant angle in the piece if the mold is so shaped, but there are limits to the amount of material which may be pressed around corners without forming cracks in the fired article. I have found that accurate pockets 20 and grooves 21 with good seats 22 can be formed by proceeding as follows:

Provide a pair of knurled spindles of a diameter barely less than the width of the groove 21 and on the ends thereof affix abrasive wheels or fine toothed milling cutters. Space these apart the distance between pockets, etc., on parallel axes. Mount a green (before firing) block 10 on a slide and move it slowly against the wheels or cutters and spindles. The wheels or cutters form the pockets 20 while the spindles form the grooves 21. Uniform flat seats 22 are formed in this way.

Although the drawings show but one ring of blocks it is intended that several rings be superimposed upon each other to form a pulpstone which has a plurality of blocks across its face i. e. in an axial direction. The marginal blocks preferably have one side which is straight, that is in a true radial plane. No illustration of these features was made because per se they are old in the art.

It will thus be seen that there has been provided by this invention an article in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

I claim:

1. A pulpstone or the like comprising a concrete center of annular shape, a plurality of blocks of bonded abrasive material on the outside of said center to form an abrasive annulus, each block having an outer abrading surface, an inner surface adjacent the center, and a plurality of faces between said surfaces, each block having a pocket in each of two faces forming a seat at the bottom thereof, there being a groove in the

block extending from each pocket to the inner surface of the block, a bar across the inner surface of the block extending between said grooves, a sleeve against each end of the bar and extending into the concrete center, bolts in the sleeves and extending beyond the sleeves and into the pockets, and means on each end of the bolts both in the pockets and embedded in the concrete, said means holding the bolts in tension and the sleeves under compression, and that portion of the blocks radially inward of the seats being under compression derived from the bolts and exerted against the seats.

2. A pulpstone or the like as claimed in claim 1 wherein the outer portions of the blocks radially outward from level of the tops of the pockets is of desired abrasive characteristics, and the inner portion of the blocks radially inward from the seats is of stronger composition regardless of its abrasive characteristics yet the blocks are integral pieces.

3. A pulpstone or the like as claimed in claim 1 in which at least some of the blocks are keyed to the concrete including a projection in one part fitting a recess in the other part.

4. A pulpstone or the like comprising a concrete center of annular shape, a plurality of blocks of bonded abrasive material on the outside of said center to form an abrasive annulus, bolts in the blocks and in the center holding the blocks to the said center, some of the blocks having portions cut out radially outward from the bolts whereby said bolts have been inserted through said cut out portions to secure said blocks to said center, and abrasive plugs inserted in said cut out portions.

5. A pulpstone or the like comprising a concrete center of annular shape, a plurality of blocks of bonded abrasive material on the outside of said center to form an abrasive annulus, each block having an outer abrading surface, an inner surface adjacent the center, and a plurality of faces between said surfaces, each block having pockets in each of two faces forming a seat at the bottom thereof, there being a groove in the block extending from each pocket to the inner surface of the block, bars across the inner surface of the block extending between said grooves, a sleeve against each end of the bars and extending into the concrete center, bolts in the sleeves and extending beyond the sleeves and into the pockets, and means on each end of the bolts both in the pockets and embedded in the concrete, said means holding the bolts in tension and the sleeves under compression, and that portion of the blocks radially inward of the seats being under compression derived from the bolts and exerted against the seats.

6. A pulpstone or the like comprising a concrete center of annular shape, a plurality of blocks of bonded abrasive material on the outside of said center to form an abrasive annulus, each block having an outer abrading surface, an inner surface adjacent the center, and a plurality of faces between said surfaces, each block having pockets in one face and opposing pockets in an opposite face forming seats at the bottoms thereof, there being a groove in the block extending from each pocket to the inner surface of the block, bars across the inner surface of the block extending between the grooves of said opposing pockets, a sleeve against each end of the bars and extending into the concrete center, bolts in the sleeves and extending beyond the sleeves and into the pockets, and means on each end of the bolts both on

the seats in the pockets and embedded in the concrete, said means holding the bolts in tension and the sleeves, the bars and that portion of the blocks radially inward of the seats under compression exerted against the seats by one of said means.

7. In a pulpstone an abrasive block having an outer abrading surface, an inner surface, a plurality of faces between said surfaces, pockets in one face and opposing pockets in an opposite face having seats at the bottoms thereof, there being a groove in the block extending from each pocket to the inner surface of the block, bars across the inner surface of the block extending between the grooves of said opposing pockets, a sleeve against each end of the bars and extending toward the center of said pulpstone, bolts in the sleeves and extending beyond the sleeves and into the pockets and means on each end of the bolts both on the seats in the pockets and at the inner ends of

8
said sleeves, said means holding the bolts in tension and the sleeves, the bars and that portion of the block radially inward of the seats under compression exerted against the seats by one of said means.

GEORGE N. JEPSON.
